UNITED STATES PATENT OFFICE.

ARTHUR K. WHITELAW, OF LOUISVILLE, KENTUCKY, ASSIGNOR TO STANDARD OIL COMPANY OF KENTUCKY, OF LOUISVILLE, KENTUCKY, A CORPORATION OF KENTUCKY.

CONDENSER.

Application filed February 16, 1922. Serial No. 536,993.

To all whom it may concern:

Be it known that I, ARTHUR K. WHITELAW, a citizen of the United States, and a resident of Louisville, in the county of Jefferson and State of Kentucky, have invented new and useful Improvements in Condensers, of which the following is a full, clear, and exact description.

This invention relates to improvements in condensers for the distillation of crude oil, and particularly over my Patent No. 1,237,848, dated August 21, 1917.

The general object of this invention is the provision of a condenser for use with a still used in the destructive distillation of crude oils in order to obtain hydrocarbon products of a low boiling point, provided with means for utilizing the crude oil to control the temperature of the vapors passing from the still to condense the undesirable high boiling point hydrocarbon fractions and return them to the still, and condensing means for acting upon the high boiling point hydrocarbon fractions not affected by the said condensing means to further eliminate the high boiling point hydrocarbons contained in the vapors coming from the still.

A further object is the provision of a condenser for use with a still used for the destructive distillation of crude hydrocarbon oils provided with means for insulating the vapors from atmospheric control and providing means for controlling the temperature of the vapors.

With the above and other objects in view, the nature of which will more fully appear as the description proceeds, the invention consists in the novel construction, combination and arrangement of parts as herein fully described, illustrated and claimed.

In the accompanying drawings showing a practical embodiment of this invention and forming part of the application.

Figure 1 is a vertical section through the condenser, showing it connected to the still and cooling coils;

Figure 2 is a cross section along the line 2—2, Figure 1.

Referring to the above-mentioned drawings, the condenser assemblage 10 is shown connected by means of the pipe 11 to the still 12 and by the pipe 13 to the cooling coils 14. The pipe 11 is provided to con-

vey vapors from the still 12 to the condenser and liquid from the condenser to the still. The pipe 13 serves to convey the vapors from the condenser to the cooling coil 14, and a valve 15 is associated with the pipe 13 for controlling the flow of these vapors.

The condenser assemblage 10 is constructed as follows: Two cylindrical casings 16 and 17 of different cross sectional area and length are provided, and the cylindrical casing 17 is supported concentric with the casing 16 by means of a plate 18 mounted in the latter. The plate 18 is spaced a distance from the head 19 which closes the lower end of the casing 16 thus forming a chamber 20 between the plate 18 and the head 19. The area between the casings 16 and 17 is closed at the bottom by the plate 18 forming a chamber 21 open at the top. Perforations 22 are provided in that portion of the plate 18 directly in line with the casing 17. A plurality of plates 23 having openings 24 extending through their centers are mounted in the casing 17 so that the openings are concentric with the casing. Open frameworks 26 are mounted on the plates 23 to support plates 25 spaced above the openings 24. These plates are slightly smaller in diameter than the diameter of the casing 17 and together with the plates 23 form a 80 baffling means for delaying the progress of the vapors through the casing 17.

Mounted on the upper end of the cylindrical casing 16 is a head 31 through which the pipe 13 projects in order to communicate with the condenser 10. A plurality of plates 27 which have openings 30 concentric with them and extending therethrough are mounted in the cylindrical casing 16 between the top of the cylindrical casing 17 and the head 31. Frames 28 are mounted on the plates 27 and support plates 29 concentric with the plates 27. These plates supported in the casing 16 form a condensing means which acts upon the hydrocarbon fractions having a high boiling point that pass through the cylindrical casing 17.

A pipe 32 extends through the casing 16 into the chamber 21 and serves as a means for feeding the crude oil into said condenser. A manually operated valve 33 for controlling the flow of the liquid into the chamber and a check valve 34 for preventing the flow of the liquid out of the chamber are positioned in the pipe 32. A pipe 35 which ex-

tends through the casing 16 has a valve 36 mounted therein and this pipe serves as a means for pumping liquid out of the chamber 21.

- 5 The operation of the condenser is as follows: A quantity of the crude oil or distillate is fed into the still 12 and the latter put into operation. Vapor containing high and low boiling point hydrocarbons passes from 10 the still 12 through the tube 11 into the chamber 20 of the condenser. From the chamber 20 the vapor passes up through the baffling means in the cylindrical casing 17, the baffle plates serving to continually force 15 the vapor outward towards the wall of the casing. As the vapors pass up through the cylindrical casing 17 crude oil is fed through pipe 32 into the chamber 21 until it floods the chamber, flowing over the upper end of 20 the casing 17. This crude oil thus forms a seal or an insulation about the casing 17, serving to protect it from changes of atmospheric temperature and also absorbing a certain amount of the heat from the vapor. 25 The crude oil flows down over the plates 25 and 23 and is mixed with the vapor in such a manner as to absorb more heat from the same. The decrease in temperature caused by the crude oil condenses the hydrocarbon 30 fractions having a high boiling point and are carried by the oil down through the casing 17 to the pipe 11 and into the still 12 where they are further treated. The hydrocarbon fractions that pass through the cylindrical casing 17 are finally acted upon by 35 the plates mounted in the top of the casing 16 and those that are condensed are also returned to the oil being fed into the still through the casing 17. The vapor which includes the hydrocarbon fractions of a lower 40 boiling point pass on up into the top of the casing 16 and finally into the pipe 13 and are conveyed to the cooling tubes 14. The valve 33 provides a means for controlling 45 the flow of crude oil into the chamber 21 and thus the temperature may be regulated by controlling the volume of oil that passes into the chamber 21. The check valve 34 prevents the oil from backing up from the 50 chamber 21 into the pipe 32.

The heat absorbed from the vapor by the crude hydrocarbon oil being fed into the still raises the temperature of the said oil to a degree sufficient to vaporize the hydrocarbons having a low boiling point and which are the hydrocarbon fractions it is desired to obtain. The vapor which carries the hydrocarbon fractions having a low boiling point are conveyed to the cooling tubes 14 where 55 the vapor is then condensed.

I would state in conclusion that while the illustrated example constitutes a practical embodiment of my invention I do not limit myself strictly to the exact details herein illustrated since manifestly the same can be

considerably varied without departing from the spirit of the invention as defined in the appended claims.

Claims.

1. A condenser of the class described, comprising an outer casing, an inner casing of similar but smaller cross section and shorter in length than the outer casing, means for supporting the inner casing concentric with the outer casing with its ends spaced a distance from the ends of the latter and for closing the area between the lower end of the inner casing and the wall of the outer casing, baffling means mounted in the outer casing and positioned above the inner casing, 70 means for conveying liquid into the outer casing to flood the inner casing, vapor inlet and liquid outlet means connected with the lower end of the outer casing and vapor outlet means leading from the upper end of 80 the outer casing.

2. A condenser of the class described for use in the distillation of crude oils, comprising two casings of similar shape but different cross sectional area and length, supporting means mounted in the larger casing spaced a distance from the bottom and having perforations extending therethrough for supporting the smaller casing concentric with the larger casing so that the ends of 95 the former terminate a distance from the ends of the latter, said supporting means serving to close the area between the lower end of the smaller casing and the wall of the larger casing to form a chamber therebetween, baffling means mounted in the smaller casing, condensing means mounted in the larger casing and positioned above the smaller casing to co-operate with the baffling means located in the latter, oil feeding means connected with the outer casing to feed oil into said chamber formed between the two casings to flood the chamber and feed the smaller casing, liquid outlet and vapor inlet means connected with the lower 100 end of the larger casing, and vapor outlet means for conveying the uncondensed vapor from the outer casing.

3. A condenser of the class described for use in the distillation of oil, comprising two casings of similar shape but different cross sectional area and length, means for mounting the smaller casing concentric with the larger casing with their ends spaced from one another, and so as to form a chamber between the casings which is closed at its lower end, baffling means located in the smaller casing, and condensing means mounted in the larger casing positioned above the baffling means mounted in the smaller casing, means for conveying crude oil into the chamber between the casings to flood the same and form an insulating layer about the inner casing and to feed oil to the same, vapor inlet and liquid outlet 110 115 120 125 130

means connected to the lower end of the outer casing to convey away the liquid passing downward through the smaller casing, and means connected to the upper end of the outer casing for conveying away the uncondensed vapor.

4. A condenser of the class described for use in the distillation of crude oils, comprising two cylindrical casings of different cross sectional area and length, a plate having perforations extending through its center mounted in the larger cylindrical casing spaced a distance from the lower end and supporting the smaller cylindrical casing concentric with the larger cylindrical casing and closing the space between the two cylindrical casings to form a chamber open at the upper end of the smaller cylindrical casing, a plurality of plates having openings extending through their centers mounted in the smaller cylindrical casing, a baffle plate supported above each opening for forcing vapor passing through said openings against the casing wall, condensing means positioned

in the larger casing above the smaller casing, and means for conveying crude oil into the chamber between the casings to form an insulating medium between the inner casing and the atmosphere and to flood the chamber to feed oil into the smaller cylindrical casing, means associated with the lower end of the larger cylindrical casing to draw off the oil fed into the smaller cylindrical casing and to feed the vapor into the casings, and means connected with the upper end of the outer casing for conveying the uncondensed vapor out of the condenser.

5. In a condenser including a main casing, an inner casing mounted in the main casing forming a chamber between them from which the inner casing may be flooded, a plurality of baffle members mounted in the inner casing obstructing the passage therethrough, and a plurality of baffle members mounted in the outer casing above the inner casing, obstructing the passage out of the outer casing.

ARTHUR K. WHITELAW.
